UNITED STATES PATENT OFFICE.

CARL A. MATSON, OF LYNN, AND ALBERT M. HOYT, OF SWAMPSCOTT, MASSACHUSETTS.

MACHINE FOR WAX-FINISHING THE EDGES OF THE HEELS OF BOOTS AND SHOES.

1,211,866.

Specification of Letters Patent.

Patented Jan. 9, 1917.

Application filed September 5, 1914. Serial No. 860,347.

To all whom it may concern:

Be it known that we, CARL A. MATSON and ALBERT M. HOYT, citizens of the United States, residing, respectively, at Lynn and 5 Swampscott, in the county of Essex and State of Massachusetts, have invented new and useful Improvements in Machines for Wax-Finishing the Edges of the Heels of Boots and Shoes, of which the following is 10 a specification.

This invention relates to a machine for wax treating and burnishing the edges of the heels of boots and shoes in which a rotary work rubbing member and a receptacle for wax are employed.

The novel features of the invention reside first in the means whereby the wax is fed from the wax receptacle to the periphery of the rotary work rubbing member and 20 second in the construction and arrangement of parts whereby the means for feeding the wax from the wax receptacle to the periphery of the rotary work-rubbing member are thrown into operation to feed said wax, as set forth, when the operator presses the heel of the shoe against the periphery of the work rubbing member. In machines of the class hereinbefore set forth it is very desirable 25 that sufficient wax should be fed to the periphery of the work rubbing member to perform the work and no more, and it is further desirable that the amount of wax fed to the work rubbing member during a given time should be capable of regulation—that is, that it should be possible for the operator to quickly and easily adjust the machine so as to feed more or less wax during a given time to the periphery of the work rubbing member as may be desired, 30 and it is also very desirable that when the work rubbing member is not in use to wax treat the edges of the heels of boots and shoes no wax should be fed to the periphery of said member. If too much wax is applied 35 to the periphery of the work rubbing member it results in applying too heavy a coat to the edge of the boot or shoe heel and also the wax is liable to run down the sides of the work rubbing member and get onto the 40 upper of the shoe, leading to considerable work in removing the same in order to perform a neat piece of work. Furthermore, if too much wax is supplied to the periphery of the work rubbing member it is thrown 45 off and is liable to be thrown in a heated condition upon the hands of the operator and on different parts of the machine to the great detriment thereof. Moreover, in machines of this class the work rubbing member is utilized for the wax treating operation for the edges of the heels of boots and 50 shoes during only about one-third of the time, the operator during the rest of the time being employed either in handling the shoe, padding with a padding brush, or in beading and in polishing with a polishing brush. When wax is being constantly applied to the periphery of the work rubbing member and not being immediately used, it 55 results in deterioration of the wax as well as the other difficulties hereinbefore set forth, and it is the object of this invention to provide a machine which, under normal conditions, will not supply wax to the periphery of the work rubbing member, but as soon as 60 the operator presses the edge of the heel against the periphery of the work rubbing member, the wax feeding means will be immediately and automatically thrown into operation by reason of this pressure and the 65 wax feeding means will then begin to transfer wax in its melted condition from the wax receptacle to the periphery of the work rubbing member in order that it may be applied to the edge of the heel which is to be 70 wax treated. The mechanism is also so constructed and arranged that when the operator removes the heel from the periphery of the work rubbing member the wax feeding means will be automatically thrown out of 75 action and the feeding of the wax stopped. 80

To these ends the invention consists in the improved mechanism whereby wax may be supplied to the periphery of a rotary work rubbing member and also said invention consists in the construction and arrangement of parts whereby, when the edge of the heel is pressed against the periphery of the work rubbing member, the feeding of the wax to said periphery will begin and 85 when said heel is removed from the periphery of the work rubbing member the feeding of said wax will cease. 90

The invention further consists in the combination and arrangement of parts set forth in the following specification and particularly pointed out in the claims thereof. 95

Referring to the drawings: Figure 1 is a

rear elevation of a portion of a wax finishing machine for boots and shoes embodying our improved mechanism for feeding the wax from the wax receptacle to the periphery of the work rubbing member. Fig. 2 is a detail sectional elevation taken on line 2—2 of Fig. 1. Fig. 3 is a sectional elevation taken on line 3—3 Fig. 1. Fig. 4 is an end elevation of a modified form of the 10 wax feeding member. Fig. 5 is a side elevation of the modified form illustrated in Fig. 4. Fig. 6 is a side elevation of another modified form of wax feeding member. Fig. 7 is a plan view of the modified form of wax feeding member illustrated in Fig. 6. Fig. 8 is a sectional elevation taken on line 8—8 of Fig. 3.

Like numerals refer to like parts throughout the several views of the drawings.

20 In the drawings, Figs. 1, 2, 3 and 8, 10 is a rotary work rubbing member preferably formed of felt or other soft material covered with cloth in accordance with the ordinary construction of such work rubbing members. 25 Said work rubbing member is fastened to a shaft 11 journaled to rotate in suitable bearings as 12 in the frame 13 of the machine. A rotary motion is imparted to the shaft 11 by a pulley not shown in the drawings, said 30 rotary member being rotated in the direction of the arrow *a* (Fig. 3).

A receptacle 14 for wax is located beneath the work rubbing member 10 and said work rubbing member preferably projects down 35 into said receptacle. The wax is kept at about the height of the dotted line *b* in said receptacle and is heated by a suitable burner 15 located beneath the receptacle 14. The wax 16 in a melted condition is fed from 40 the receptacle 14 to the periphery of the work rubbing member 10 by a series of fingers 17, formed preferably of spring wire, which are fastened to a holder 18, said spring fingers 17 and the holder 18 constituting 45 an arm which is fastened to a rock-shaft 19.

The rock-shaft 19 is adapted to rock in a bearing 20 formed in the wax receptacle 14 and said rock-shaft has fastened to its outer 50 end an arm 21 which is slotted at 22 to receive a stud 23, said stud being clamped to the arm 21 by a clamp nut 24. A link 25 is pivoted upon the stud 23 at one end thereof and is connected by a pin 26 at its other 55 end to a rocker arm 27. Said rocker arm has rotatably mounted thereon a cam roll 28 which is arranged to bear against the periphery of the cam 29 fastened to a shaft 30. The shaft 30 is journaled to rotate in 60 bearings 31 on the frame of the machine and has fastened thereto a ratchet 32 at the opposite end thereof from that to which the cam 29 is fastened.

The ratchet 32 is held in position against 65 accidental rotation by a roll 33 which bears

against the periphery of said ratchet and is mounted upon a vertical pin 34 adapted to slide in a recess 35 in the wax receptacle, said roll being pressed against the periphery of said ratchet by a spring 36 which is enclosed within the recess 35 and bears against the lower end of the pin 34.

An intermittent rotary motion is imparted to the shaft 30 by a pawl 37 which is pivoted on a pin 38 fast to the pawl carrier 39 which is mounted to rock upon the cam shaft 30 and has a rocking movement imparted thereto by an eccentric rod 40 which is connected to an eccentric strap 41, said eccentric strap encircling an eccentric 42 formed upon one member 70 of a clutch 71. Said member 70 is loose upon the driving shaft 11 and has a conical face 72 thereon adapted to be engaged by a similar conical face 73 formed upon the other member 74 of said clutch 71. The member 74 is fastened by a set-screw 75 to the hub 76 of the rotary work rubbing member 10. Said rotary work rubbing member is loosely mounted upon the shaft 11 so that the same may be rotated to a limited extent independently of said shaft and moved longitudinally upon said shaft. It will thus be seen that the rotary work rubbing member and the member 74 of the clutch 71 are, in effect, a single 95 piece and move as one piece. A pin 77 fast to the shaft 11 projects into an inclined slot 78 formed in the hub 76 of the rotary member 10. The parts 70 and 74 of said clutch are normally held apart—that is, with their 100 faces 72 and 73 out of frictional contact with each other, by a pin 79 which slides in the recess 80 extending longitudinally within the member 70, said pin being held with its outer end in frictional engagement with the 105 adjacent end of the member 74 by a spring 81.

The pawl 37 is held in engagement with the teeth of the ratchet 32 by a spring 43 and is thrown out of engagement with said 110 teeth by a tripper consisting of a pin 45 fast to an arm 46 on a lever 47.

The lever 47 is pivoted upon the shaft 30 and is locked in position by a spring-actuated locking pin 48 which is held by a spring 115 49 in engagement with any one of the teeth 50 upon the lower end of an arm 51 on the lever 47. The lever 47 is set in different positions by hand and is locked in the position in which it is set by the spring pin 48. As 120 said lever is moved in one direction or the other the pin 45 will be engaged sooner or later, respectively, by an incline 52 on the tail-piece 53 of the pawl 37. Evidently as the lever 47 is moved to set the pin 45 upwardly (Fig. 3) the incline 52 on the tail-piece 53 will engage said pin 45 sooner than when said pin is set downwardly from the position shown in Fig. 3 and thus the pawl 125 will be thrown out of engagement with the 130

ratchet 32 at different times, according to the location of the pin 45, and will also be allowed to drop into engagement with said teeth at different times according to the position of said pin. Consequently, the feed of the ratchet 32, or the distance to which it is moved at each rotation of the shaft 11, will be increased or diminished according to the position in which the tripper pin 45 is set. Thus the number of times that the spring fingers 17 are brought into and out of contact with the periphery of the work rubbing member as compared with a given length of time during which the heel of the shoe is held in contact with said work rubbing member may be increased or diminished according to the position in which the tripper pin 45 is set by means of the lever 47.

20 The general operation of the mechanism hereinbefore specifically described and illustrated in Figs. 1, 2, 3 and 8 is as follows: Assuming the wax in the wax receptacle 14 to be melted by means of a flame from the burner 15 and the shaft 11 to be rotated in the direction of the arrow *a*, the operator places the edge of the heel of a shoe against the periphery of the work rubbing member 10 and as he does so he applies a frictional 25 resistance to the free rotation of said work rubbing member which results in the pin 77 moving forwardly in the slot 78 and, as said slot is inclined this action will cause the member 74 of the clutch 71 to be forced toward the member 70 of said clutch until the 30 surfaces 73 and 72 are pressed into frictional contact with each other, the pin 79 being pushed backwardly against the resistance of the spring 81. The parts 74 and 70 of 35 the clutch thus being clutched together will rotate the eccentric 42 and thus, through the eccentric strap 41 and eccentric rod 40, a rocking motion will be imparted to the pawl carrier arm, thus causing the pawl 37 to 40 rotate the ratchet 32 to a greater or less extent according to the position of the tripper pin 45, as hereinbefore described. As said ratchet is rotated the shaft 30 will be rotated and the cam 29 will be rotated in the 45 direction of the arrow *a*, thus moving the rocker arm 27 and through the link 25 rocking the arm 21 and the rock-shaft 19 so as to move the fingers 17 alternately from the position shown in full lines to that shown in dotted lines (Fig. 3). This action will 50 intermittently carry wax by means of the fingers 17 into contact with the periphery of the work rubbing member 10 and the amount of wax delivered may be increased 55 by moving the lever 47 toward the right (Fig. 3) and decreased by moving the same toward the left (Fig. 3), the pawl in the former case being allowed to drop into the teeth of the ratchet sooner than in the 60 latter case.

As soon as the heel has been sufficiently wax treated and burnished, the operator removes the edge of the heel from contact with the periphery of the work rubbing member 10 and as soon as he does so the 70 part 74 will be moved away from the part 70 by the spring 81 and spring pin 79, thus disengaging the two parts of the clutch and allowing the shaft 11 to rotate while the member 70 of the clutch remains stationary 75 and the wax feeding means is thus thrown out of action so that no more wax will be fed to the periphery of the work rubbing member 10 until the operation hereinbefore described is repeated.

80 While we have described our invention and illustrated the same as particularly adapted to be used in that form of machine in which wax is contained in a wax pot and from said wax pot conveyed to the periphery of a work rubbing member by certain specific mechanism, we do not wish to be understood as limiting our invention to this particular embodiment thereof, as the wax may be conveyed to the work rubbing 85 member in a variety of ways and by different mechanisms without departing from the spirit of our invention, particularly that portion of our invention which consists in throwing the wax supplying mechanism 90 into operation by pressing against the periphery of the work rubbing member or by offering resistance to the free rotation of said work rubbing member, howsoever that 95 resistance may be applied.

100 By making the fingers 17 of spring wire, it is evident that the same will conform to the convex cross-sectional contour of the periphery of the work rubbing member 10, so that said fingers will automatically adapt 105 themselves to the shape of said periphery and the wax will be applied in strips extending around the periphery of said work rubbing member. The amount of wax which is applied to the periphery of the 110 work rubbing member, as hereinbefore described, may be increased by increasing the number of times that the fingers 17 are brought into contact with the periphery of the work rubbing member 10, per minute.

115 Referring to Figs. 4 and 5: In Figs. 4 and 5 a modified form of wax feeding member is illustrated in which the fingers 54, which feed the wax to the work rubbing member, do not necessarily yield in themselves, but are fastened to holders 55, all of which holders are pivotally mounted upon a rod 56 which is fastened at its opposite ends to ears 57 forming a part of a carrier 58 which is fastened to a rock-shaft 120 59, said shaft being adapted to fit in the bearing 20 and to be rocked by the arm 21 similarly to the rock-shaft 19 in the form of our invention embodied in Figs. 1, 2, 3 and 8. Each of the holders 55 is provided 125 130

with a spring 60 which is fastened to the carrier 58 and has its free end bearing against the holder 55, so that when the shaft 59 is rocked by the mechanism hereinbefore described the fingers 54 will be brought to bear against the periphery of the work rubbing member 10, and the springs 60 will yield so as to allow said fingers to conform in series to the convexly curved periphery of said work rubbing member. Thus said fingers will yield, although not necessarily themselves made of spring metal.

In Figs. 6 and 7 another modified form of wax feeding member is illustrated in which 61 are the fingers and 62 are the holders to which said fingers are fastened, said fingers being supported upon a rod 63 extending therethrough, and the holders 62 being adjustably fastened to said rod by means of screws 64. The rod 63 is clamped to ears 65 upon the carrier 66 by a clamp nut 67. The carrier 66 is fastened to a rock-shaft 69 which is adapted to rock in the bearing 20. It will be seen that by adjusting the different holders 62 to the proper position and fastening them to the rod 63 by the set-screws 64 and then tightening the rod 63 in the ears 62, by means of the clamp-nut 67, the fingers 60 may be arranged in series in a curve adapted to conform to the curve forming a cross-sectional contour of the periphery of the work rubbing member.

Having thus described our invention, what we claim and desire by Letters Patent to secure is:

1. A machine for wax finishing the edges of the heel of a boot or shoe having, in combination, a rotary work-rubbing member, a receptacle for wax, a plurality of fingers arranged to project into wax in said receptacle and mechanism adapted to intermittently move said fingers from said wax into and out of contact with the periphery of said work-rubbing member.

2. A machine for wax finishing the edges of the heel of a boot or shoe having, in combination, a rotary work rubbing member having a periphery curved in cross section, a receptacle for wax, a plurality of fingers arranged in series in a curve substantially like that of said periphery and mechanism adapted to intermittently move said fingers from said wax into and out of contact with the periphery of said work rubbing member.

3. A machine for wax finishing the edges of the heel of a boot or shoe having, in combination, a rotary work rubbing member, a receptacle for wax, a plurality of spring fingers arranged to project into wax in said receptacle and mechanism adapted to intermittently move said fingers from said wax into and out of contact with the periphery of said work rubbing member.

4. A machine for wax finishing the edges of the heel of a boot or shoe having, in combination, a rotary work rubbing member, a receptacle for wax, a rock-shaft, a plurality of fingers adapted to be adjusted at different angles on said rock-shaft and arranged to project into wax in said receptacle and mechanism adapted to intermittently move said fingers from said wax into and out of contact with the periphery of said work rubbing member.

5. A machine for wax finishing the edges of the heel of a boot or shoe having, in combination, a rotary work rubbing member, a receptacle for wax, a plurality of fingers arranged to project into wax in said receptacle, mechanism adapted to intermittently move said fingers from said wax into and out of contact with the periphery of said work-rubbing member and means to vary the number of times per minute that said fingers are brought into and out of contact with said work rubbing member.

6. A machine for wax finishing the edges of the heel of a boot or shoe having, in combination, a rotary work rubbing member, a receptacle for wax, a rock-shaft, an arm on said rock-shaft arranged to project into wax in said receptacle and a pawl and ratchet mechanism adapted to rock said shaft and intermittently move said arm from said wax into and out of contact with the periphery of said work-rubbing member.

7. A machine for wax finishing the edges of the heel of a boot or shoe having, in combination, a rotary work rubbing member, a receptacle for wax, a rock-shaft, an arm on said rock-shaft arranged to project into wax in said receptacle, a shaft, a cam and a ratchet fast to said shaft, a pawl engaging said ratchet, a pawl carrier on which said pawl is pivoted, means to rock said pawl carrier whereby an intermittent rotary motion is imparted to said last-named shaft and mechanism actuated by said cam adapted to rock said rock-shaft whereby said arm is intermittently moved from said wax into and out of contact with the periphery of said work-rubbing member.

8. A machine for wax finishing the edges of the heel of a boot or shoe having, in combination, a rotary work rubbing member, a receptacle for wax, a rock-shaft, an arm on said rock-shaft arranged to project into wax in said receptacle, a shaft, a cam and a ratchet fast to said shaft, a pawl engaging said ratchet, a pawl carrier on which said pawl is pivoted, means to rock said pawl carrier whereby an intermittent rotary motion is imparted to said last-named shaft, mechanism actuated by said cam adapted to rock said rock-shaft whereby said arm is intermittently moved from said wax into and out of contact with the periphery of

5 said work rubbing member, and a tripper adapted to engage said pawl and throw it out of engagement with said ratchet at one end of the rocking movement of said carrier.

9. A machine for wax finishing the edges of the heel of a boot or shoe having, in combination, a rotary work rubbing member, a receptacle for wax, a rock-shaft, an arm on 10 said rock-shaft arranged to project into wax in said receptacle, a shaft, a cam and a ratchet fast to said shaft, a pawl engaging said ratchet, a pawl carrier on which said pawl is pivoted, means to rock said pawl 15 carrier whereby an intermittent rotary motion is imparted to said last-named shaft, mechanism actuated by said cam adapted to rock said rock-shaft whereby said arm is intermittently moved from said wax into 20 and out of contact with the periphery of said work rubbing member and a tripper adapted to engage said pawl and throw it out of engagement with said ratchet at one end of the rocking movement of said carrier, said tripper arranged to be placed in 25 different positions relatively to said pawl whereby the number of times per minute said arm is brought into and out of contact with said work rubbing member may be 30 varied.

10. A machine for wax finishing the edges of the heel of a boot or shoe having, in combination, a work rubbing member having a periphery curved in cross section, a receptacle for wax and a feed arm comprising a 35 series of spring fingers adapted to yield and conform to said periphery when brought into contact therewith.

11. A machine for wax treating the edges 40 of the heel of a boot or shoe having, in combination, a rotary driving shaft, a rotary work rubbing member loosely mounted thereon, means constructed and arranged to supply wax to the periphery of said work 45 rubbing member, mechanism constructed and arranged to move said wax supplying means into and out of contact with the periphery of said work rubbing member a clutch constructed and arranged to operate 50 said mechanism, said clutch being normally out of operative connection therewith and means operated by pressure on said work rubbing member constructed and arranged to throw said clutch into operative connection 55 with said shaft, whereby said mechanism may be actuated to move said wax supplying means into and out of contact with the periphery of said work rubbing member.

12. A machine for wax treating the edges 60 of the heel of a boot or shoe having, in combination, a rotary driving shaft, a rotary work rubbing wheel loosely mounted thereon, means constructed and arranged to supply wax to the periphery of said work 65 rubbing wheel, said means including a clutch,

one member of said clutch being loosely mounted on said shaft, the other member of said clutch being fastened to said work rubbing wheel and a pin on said shaft projecting into an inclined slot in said work rubbing member, whereby when resistance is applied to the free rotation of said work rubbing member said pin will force said members of said clutch into operative relation with each other and said wax applying means will be operated. 70

13. A machine for wax treating the edges of the heel of a boot or shoe having, in combination, a rotary driving shaft, a rotary work rubbing wheel loosely mounted thereon, means constructed and arranged to supply wax to the periphery of said work rubbing member, said means including a clutch, one member of said clutch being loosely mounted on said shaft, the other member of said clutch being fastened to said work rubbing wheel, a pin on said shaft projecting into an inclined slot in said work rubbing member, whereby when resistance is applied to the free rotation of said work rubbing member said pin will force said members of said clutch into operative relation with each other and said wax applying means will be operated, and a spring interposed between said members to separate the same whereby 80 when said work rubbing wheel is allowed to rotate freely said clutch will become inoperative and said wax applying means will cease to operate. 85

14. A machine for wax finishing the edges 90 of the heel of a boot or shoe having, in combination, a driving shaft, a rotary work rubbing member mounted on said driving shaft, a receptacle for wax, a plurality of fingers arranged to project into wax in said receptacle, mechanism adapted to intermittently move said fingers from said wax into and out of contact with the periphery of said work rubbing member, a clutch mounted on 95 said driving shaft and constructed and arranged to operate said mechanism, said clutch being normally out of operative connection therewith and means operated by pressure on said work rubbing member constructed and arranged to throw said clutch 100 into operative connection with said shaft whereby said mechanism may be actuated to move said fingers into and out of contact with the periphery of said work rubbing member. 105

15. A machine for wax finishing the edges 110 of the heel of a boot or shoe having, in combination, a rotary work rubbing member, a rotary driving member connected to said work rubbing member and movable relatively thereto, a receptacle for wax, mechanism constructed and arranged to feed wax from said receptacle to the periphery of said work rubbing member, said mechanism being normally out of operation, and means 115 120 125 130

operated by the relative movement of one of said rotary members to the other adapted to operate said wax feeding mechanism whereby, when resistance is applied to the free rotation of said work rubbing member, said wax feeding mechanism will be operated.

In testimony whereof we have hereunto

set our hands in presence of two subscribing witnesses.
